IMPRESSION TRANSFERRING DEVICE

Filed May 5, 1927

FIG. I.

FIG. II.

FIG. III.

INVENTOR:

SAMUEL A. NEIDICH,

By *Arthur E. Lange*,
Attorney.

UNITED STATES PATENT OFFICE

SAMUEL A. NEIDICH, OF EDGEWATER PARK, NEW JERSEY, ASSIGNOR TO NEIDICH PROCESS COMPANY, OF BURLINGTON, NEW JERSEY, A CORPORATION OF DELAWARE

IMPRESSION-TRANSFERRING DEVICE

Application filed May 5, 1927. Serial No. 189,050.

My invention may be employed with particular advantage in conjunction with type-writing machines of the plane platen type; for instance, such manifolding machines as 5 are manufactured by Elliott-Fisher Company. In such machines, several carbon paper webs are wound in a single roll, from which they are withdrawn transversely to several webs of paper upon which original and transferred impressions are to be made; the carbon paper webs being extended between the other webs. In such machines, the carbon paper normally remains stationary, while 10 the other webs are shifted, step by step, the length desired for successive sheets of writing; the manifold written sheets, both original and copies, being withdrawn, together, from between the carbon webs, and torn off their webs, thus leaving successive blank portions of the latter extending between the carbon webs. The carbon webs may remain stationary until the used portion thereof is 15 worn out; whereupon, the carbon webs may be intermittently progressed to present unused portions thereof over the platen; and 20 between the other webs.

It has been found in practice that the stresses from the type impacts upon such transfer webs rupture the latter and render 25 them worthless, before the transfer coating thereof has been used to the greatest possible extent. In other words, the life of such transfer webs would be very much longer if the paper element thereof were as durable 30 as the carbon coating thereon.

Therefore, it is the object and effect of my invention to lengthen the normal life of transfer webs, and particularly of the manifold type aforesaid, by interposing, parallel with 35 the transfer web, what I shall hereinafter term a shield web; having the function and effect of minimizing the stresses imposed upon the transfer webs by the type impacts; so as to render the transfer webs abnormally 40 durable, and at least as durable as the transfer coating thereon, and thus lessen the cost of transfer webs for a given number of type-written impressions thereon.

In the form of my invention hereinafter 45 described; the shield web is a primarily plane,

coagulated, gelatinous, amorphous, film of artificial cellulose, such as may be produced by coagulating or precipitating viscose, (liquid cellulose sulpho-carbonate or thio-carbonate) or other suitable cellulose solution; for instance, nitro-cellulose; or cellulose dissolved in ammoniacal copper oxide; or in zinc chloride; or acetic anhydride, etc.

My invention includes the various novel features of construction, arrangement and procedure hereinafter more definitely specified.

In said drawings:

Fig. I is a diagrammatic plan view of manifold transfer webs arranged transversely to 55 and in coordinate relation with, webs of paper which are to be written upon, being typical of the arrangement of such webs in a plane platen typewriting machine of the character above contemplated.

Fig. II is an elevation of said webs as seen from the lower edge of Fig. I.

Fig. III is a view similar to Fig. II, but showing a modified form of my invention.

In said figures; 1 indicates a commercial 65 manifold roll of carbon paper which, for the Elliott-Fisher machine, is wound involutely upon a core 2 having rectangular sockets 3 in the opposite ends thereof for engagement with a square shaft or shafts 4 by which the roll may be turned. Said roll is conveniently disposed at the right hand side of the machine, and a similar core 6, fitted upon the square shaft 7, is arranged at the left hand side of the machine, so that the worn carbon 70 webs may be intermittently wound thereon in a tape-up roll 9 and be thus withdrawn from the supply roll 1 on the core 2.

As indicated in Fig. II; said manifold transfer web roll 1 includes six webs 8; which 75 may be ordinary carbon paper, to wit, webs of tissue paper coated, upon their inner faces, which are presented downward in Fig. II, with what is known as carbon "dope," i. e., a mixture of powdered carbon and a waxy material, for instance, carnauba wax, mixed with vaseline. The shield web 10, of the same dimensions as the transfer webs 8, is wound therewith on said core 2, so as to be presented 80 at the outer surface of the roll 1; thus being 100

presented directly beneath the top web 12 which is to receive the ribbon imprint in the series of seven webs 12 to 18 inclusive, of which the webs 13 to 18 inclusive are to receive transfer impressions, and all of which are primarily wound in the manifold roll 20 supported upon the shaft 21 and arranged to be intermittently shifted in the direction of the arrow marked thereon in Fig. I; said webs 12 to 18 inclusive being withdrawn, step by step, as above contemplated.

As above noted; said shield web 10 is preferably a thin film of artificial cellulose and, if of the grade of artificial cellulose known commercially as "cellophane," need not be more than .0005 of an inch thick; which thickness is known commercially as No. 300. Such a shield web is not only more durable than any carbon paper web, but far more durable than any paper web of any kind thin enough to be capable of transmitting a type impression.

In the form of my invention shown in Figs. I and II, the shield web 10 being co-extensive with the transfer webs 8, is shifted with the latter to the take-up roll 9 at intervals determined by the depletion of the transfer material from the transfer webs 8. Such depletion occurs while the shield web 10 remains intact and capable of further use; but such movement of the transfer webs, of course simultaneously removes the portion of the shield web 10 coinciding with the worn and discarded portion of the transfer webs 8; so that the shield web 10 is not thus used as economically as it might be. Therefore, I have shown, in Fig. III, a shield web 22, which is a plane sheet stretched between opposite supports 23, which may be parallel spring clips by which said shield web is removably held stationary beneath the web 25 upon which the ribbon copy imprint is to be made, and over the top of the transfer web 26 which extends above the web 27 upon which the transfer imprint is to be made. In such arrangement; the shield web 22 may be used until it is worn out, regardless of the durability of the transfer web 26 which is used in cooperative relation therewith.

Of course, in an ordinary typewriting machine, a shield web may be interposed between the sheet which is to bear the ribbon imprint and the first carbon paper sheet which is to transfer such imprint; or in any other situation where such shield web may serve to prolong the life of a transfer web. However, said artificial cellulose web is far more costly than any paper; being \$1.25 per pound in 500-pound lots and, therefore, in any embodiment of my invention it is desirable to have the shield web independent of the web or webs which it is to protect; so as to minimize the quantity of the shield material used with respect to the quantity of the transfer webs used therewith.

Therefore, I do not desire to limit myself to the precise details of construction and arrangement herein set forth, as it is obvious that various modifications may be made therein without departing from the essential features of my invention, as defined in the appended claims.

I claim:

1. The combination with a transfer web, having a coating of material arranged to be detached therefrom by impact on said web; of a flexible shield web immediately adjacent to said transfer web and formed of an amorphous fabric more durable than said web, or any paper thin enough to be capable of transmitting a legible type impression, and arranged to resist destructive wear upon said transfer web; the transfer web being independent of the shield web, and movable relatively to the shield web; and said shield web being adapted to be held stationary with respect to a typewriting machine, during its use; and means arranged to detachably hold said shield web stationary during its use; whereby said shield web may be released from said machine, when worn out, and be removed and replaced by a new shield web, independently of the transfer web.

2. The combination with a transfer web, having a coating of material arranged to be detached therefrom by impact on said web; of a flexible shield web immediately adjacent to said transfer web and formed of an amorphous fabric more durable than said web, or any paper thin enough to be capable of transmitting a legible type impression, and arranged to resist destructive wear upon said transfer web; including means arranged to hold the shield web stationary, while moving the webs of carbon paper relatively thereto.

3. The combination with a transfer web, having a coating of material arranged to be detached therefrom by impact on said web; of a flexible shield web immediately adjacent to said transfer web and formed of an amorphous fabric more durable than said web, or any paper thin enough to be capable of transmitting a legible type impression, and arranged to resist destructive wear upon said transfer web; including means arranged to hold the shield web stationary, while moving the webs of carbon paper relatively thereto, including opposite stationary supports between which said shield web is stretched; axial cores, at respectively opposite ends of said carbon webs, and means arranged to rotate said cores to unwind said carbon webs from one core and wind them upon the other.

4. The combination with a transfer web, having a coating of material arranged to be detached therefrom by impact on said web; of a flexible shield web immediately adjacent to said transfer web and formed of an am-

phous fabric more durable than said web, or any paper thin enough to be capable of transmitting a legible type impression, and arranged to resist destructive wear upon said transfer web; including opposite stationary supports and spring means connected therewith adapted to hold said shield web stretched between said supports in stationary position.

5. The combination with a transfer web, having a coating of material arranged to be detached therefrom by impact on said web; of a flexible shield web immediately adjacent to said transfer web and formed of an amorphous fabric more durable than said web, or any paper thin enough to be capable of transmitting a legible type impression, and arranged to resist destructive wear upon said transfer web; including a stationary support and means arranged to detachably hold said shield web stationary on said support, during the relative movement of the carbon paper.

In testimony whereof, I have hereunto signed my name at Burlington, New Jersey, this 26th day of April, 1927.

SAMUEL A. NEIDICH.
